UNITED STATES PATENT OFFICE

FRED BISZANTZ, OF GALION, OHIO, ASSIGNOR TO THE CENTRAL OHIO STEEL PRODUCTS COMPANY, OF GALION, OHIO, A CORPORATION OF OHIO

DESIGN FOR A BURIAL VAULT

Application filed February 28, 1933. Serial No. 47,353. Term of patent 7 years.

To all whom it may concern:

Be it known that I, FRED BISZANTZ, a citizen of the United States, residing at Galion, in the county of Crawford and State of Ohio, have invented a new, original, and ornamental Design for a Burial Vault, of which the following is a specification, reference being had to the accompanying drawing, forming part thereof.

I claim:—

The ornamental design for a burial vault, as shown.

FRED BISZANTZ.
